UNITED STATES PATENT OFFICE

ROY E. CONLEY AND OTTO M. CONLEY, OF FOSTORIA, OHIO

ELECTRIC JIFFY CREAMER

Application filed August 27, 1930. Serial No. 478,241.

Our present invention has reference to a creasing device for fabrics, and is principally designed as a means for creasing the sleeves of coats, trousers and like garments when the latter are suspended from hangers and wherein the creasing operation is obtained in an easy, quick and thoroughly effective manner.

A still further object is the provision of a fabric or clothing creasing device in which the creasing plates or irons are electrically heated and in which the device is manipulated by a single operator, so that the device may be brought readily and easily over the entire portion of the garment to be creased and the creasing operation thus obtained in an easy and positive manner.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a side elevation of our invention.

Figure 2 is an end view thereof.

Figure 3 is a top plan view thereof.

Figure 4 is a transverse sectional view approximately on the line 4—4 of Figure 1.

Figure 5 is a fragmentary elevation with parts broken away to illustrate the manner in which one of the plugs is connected with one of the heating coils.

Figure 6 is a perspective view looking toward the inner face of one of the heating plates.

Figure 7 is a plan view to illustrate the resistance wire employed.

Figure 8 is a perspective view of the clip that connects the flanged end of the plug to the flanged end of the metal element to which the heating coil is secured.

As disclosed by the drawings we make use of two flat metal plates 1 respectively. The plates on their inner faces are formed with continuous thickened portions 2 that afford continuous shoulders 3 between the upper ends and edges of the plates 1.

Arranged against the inner face 2 of each of the plates 1 there are spaced strips of non-electric conducting material such as mica or the like. These strips are indicated by the numeral 4 and between each pair of strips there is arranged a heating coil 5. The ends of the coil are connected to metal plates 6 and 7, respectively, the plates 7 being in the nature of a strip and has one end projecting through a notched upper corner in the plates 4. This end is formed or offset, as at 8. The second plate is substantially V-shaped in plan and has its reduced end projecting beyond the strips and bent or flanged, as at 9. The plates are held in contacting relation by an inner metal plate 10 which is secured to the outer or face plate 1 by bolts 11. Between the bolts 11 the inner metal plate 10 is provided with a threaded opening 12.

The plates 10 are of the same size as the inner faces 2 of the plates 1, and arranged over the ends and edges of the said plates 10 and likewise arranged over the shoulders 3 provided between the inner and outer faces of the plates 1 there are the flanged covering members 13 of the improvement. These members may be integrally formed of some suitable hardened insulated material and the outer faces of the said cover plates are thickened and slightly rounded and secured to the plates 10 by screws 14 that pass through suitable openings in the said cover plates and also are threaded in the openings 12. Before the cover plates are positioned metal channelled clips 15, such as disclosed by Figure 8 of the drawings are arranged over the flanged ends 9 of the plates 7 and likewise receive therein the lower flanged ends of substantially U-shaped metal plates 16. The U-shaped plates are held on flanged tubes 17 of insulating material through the medium of nuts 19, and the nuts have connected thereto the coils of a bridge member 20 that passes through upper tubes of insulating material 21, whereby the

respective plates 7 are electrically connected.

The plugs for introducing the electricity into and out of the respective metal plates or flap jaws of the improvement are indicated by the numeral 24 and have their lower ends straight and passed through one end of the casing or covering plates 13 and held therein by nuts 25, respectively. The inner nut holds against the end face of each of the cover plates a substantially U-shaped metal member 26 and arranged over the outer flange of the said metal member and over the flange 9 on the end plates for the heating coils there are the channeled clips 15, and whereby an electric connection is obtained between the heating coils in both of the plates or creasing jaws 1.

Each of the cover members 13 has secured to its ends upstanding arms 27, each of the same length and each of the arms is approximately centrally formed with inwardly directed ears 28 which are arranged inlapping relation at the respective ends of the device. There is passed through these ears pivots 30. The upper ends of the respective pairs of arms 27 have fixed thereon handle members 31 of insulating material and between the oppositely disposed pairs of insulated handles there are arranged coiled pressure springs 32, the tension of the springs being sufficient to hold the flat presser plates or irons 1 tightly against each other.

A conductor wire is plugged in a house circuit. The conductor wires are, of course, insulated and have their ends provided with two sockets to receive the respective plugs 24. The flow of electricity through the conductor wire is preferably controlled by a switch. When the creasing plates or what we will term irons 1 are sufficiently heated, and after the garment to be creased has been suspended from a suitable hanger the operator exerts a pressure against the handles 31, thereby swinging the irons 1 to open position so that they can receive therebetween the portion of the goods or garment to be pressed. The operator places his disengaged hand upon the garment so as to hold the same in proper position to be creased and by regulating the pressure upon the handles 31, can move the device over the garment and thereby may easily, quickly and efficiently crease the said garment.

The construction of the improvement and the advantages thereof will, it is thought, be apparent to those skilled in the art to which such invention relates without further detailed description.

Having described the invention, we claim:

60 In a hand operated clothes creasing device, two contacting irons, each including an outer plate and an inner plate which are insulated from each other, heating coils between the plates, metal members having offset ends secured to the ends of the coils, a cover of insu-

lating material for each pair of plates, metal plugs passing through each cover, metal clips for connecting the plugs to the offset ends of one of the metal strips in each of the irons, tubes of insulating material on the cover plates, a wire coil passing through the tubes and entering the cover plates, metal clips for connecting the coil to the offset end of the second metal strip in each of the irons, arms secured to the ends of the irons having inwardly directed ears arranged inlapping relation and pivotally connected, a handle member secured between the ends of the respective irons, and springs between the opposed handle members exerting a pressure thereagainst for forcing the handles away from each other and the irons toward each other.

In testimony whereof we affix our signatures.

ROY E. CONLEY.
OTTO M. CONLEY.
